UNITED STATES PATENT OFFICE

ROBERT HERRMANN, OF NEW YORK, N. Y.

FITTED TRAVELING BAG

Application filed February 9, 1927. Serial No. 166,997.

This invention is a fitted traveling bag, having a body portion, an intermediate portion hinged to the body, and a cover hinged to the intermediate portion. The intermediate portion is provided with a centrally disposed, open-topped slideway. A toilet case, which is a complete unit in itself fitted with a number of toilet articles and having its own cover, with a mirror on the inside of the cover, slides 10 in and out of this slideway, and is removable therefrom as a unit.

In traveling, a woman often has occasion to use, with some frequency, certain toilet articles. These more commonly used articles 15 are in the removable toilet case, and so are readily accessible without disturbing or unpacking the rest of the traveling bag; the entire toilet case may be removed as a unit, and carried to the washroom, without the necessity of carrying the entire traveling bag.

More specifically, the open-topped guideway is provided with a pair of lateral overhanging flanges, covered with leather or otherwise finished to harmonize with the finish 25 of the bag, the toilet case being slidable in and out under these flanges.

Referring now to the drawings, illustrating the preferred embodiment of the invention,

Fig. 1 is a perspective view of the traveling bag, and,

Fig. 2 is a longitudinal cross section, showing the invention.

The traveling bag comprises a body portion 35 5, an intermediate portion 6 hinged to the body, and a unitary cover 7 hinged to the intermediate portion.

The intermediate portion is provided with a centrally disposed, open-topped guideway 8, 40 flanked by compartments 9 having covers 10.

Bordering the open-topped guideway or slideway 8 is a pair of over-hanging flanges 11, located substantially in the plane of the upper surface of the intermediate member 6, 45 and projecting into the open-topped space 8. The flanges 11 are preferably made of metal, covered or finished to harmonize with the finish of the bag.

A toilet case 12, having a cover 13, with a 50 mirror 14 on the inside thereof, the cover be-

ing hinged to the body of the toilet case along the line 15, slides in and out of the open-topped guideway, the over-hanging flanges 11 engaging over the sides 16 of the toilet case. The cover 13 of the toilet case may be 55 secured by an appropriate fastening device 17.

The intermediate portion is secured to the body portion by suitable fastening devices 18 and 18' and the cover of the bag is secured to the front of the removable toilet case 12 by 60 cooperating fastening devices 19 and 19'.

The toilet case is slidable in and out of the guideway, and removable therefrom as a unit, and is provided with the more commonly used 65 toilet articles, thereby eliminating the necessity of handling the entire traveling bag when the user only needs the toilet accessories in the removable case 12.

However, the toilet case can be used in conjunction with the rest of the traveling bag, as 70 shown in the perspective view, the whole combination serving practically as a dressing table.

I claim as my invention:—

1. A fitted traveling bag comprising a 75 body, an intermediate portion hinged to the body and coextensive therewith, a unitary cover hinged to the intermediate portion and coextensive therewith the intermediate portion having a centrally disposed open-topped slideway, and a removable toilet case, having 80 a cover, slideable in and out of said guideway and removable therefrom as a unit.

2. A fitted traveling bag comprising a body, an intermediate portion hinged to the body, a cover hinged to the intermediate portion, a removable box-like toilet case slidably carried by the intermediate portion, the toilet case having a cover, and flanges carried by the intermediate portion substantially in the 85 plane of its upper surface, the toilet case being slidable in and out below such flanges.

3. A fitted traveling bag comprising a body, an intermediate portion hinged to the body, a cover hinged to the intermediate portion, the intermediate portion having a centrally disposed, open-topped slideway with laterally disposed overhanging flanges substantially in the plane of the upper surface of the intermediate portion, and a toilet case, 90

having a cover, the toilet case being slidable in and out of the guideway and removable therefrom as a unit.

4. A fitted traveling bag comprising a body, an intermediate portion hinged to the body, a unitary cover hinged to the intermediate portion, the intermediate portion having a centrally disposed, open-topped slideway, a removable toilet case, having a cover, the toilet case being slidable in and out of said guideway and removable therefrom as a unit, means for securing the intermediate member to the body, and means for securing the cover of the traveling bag to the slidable toilet case.
